United States Patent Office

Des. 202,416

Patented Sept. 28, 1965

202,416

VEHICLE

Robert N. Hubbach, Pontiac, Bernard N. Smith, Oak Park, and Charles H. Stewart, Royal Oak, Mich., assignors to General Motors Corporation, Detroit, Mich., a corporation of Delaware

Filed Dec. 10, 1964, Ser. No. 32,983

Term of patent 7 years

(Cl. D14—3)

FIGURE 1 is a side elevational view of a vehicle, showing our new design;

FIGURE 2 is a top plan view;

FIGURE 3 is a front elevational view; and

FIGURE 4 is a rear elevational view.

The dominant features of our design reside in the full line portions of the drawings.

We claim:

The ornamental design for a vehicle, substantially as shown and described.
